United States Patent Office

Des. 224,998
Patented Oct. 31, 1972

224,998

TOOTHPASTE TUBE

Van Vechten Sayre, Chatham Township, Morris County,
and Hugh R. Kirkpatrick, New Vernon, N.J., and
Harry Zelenko, New York, N.Y., assignors to Interna-
tional Flavors & Fragrances Inc., New York, N.Y.

Filed May 26, 1971, Ser. No. 147,291

Term of patent 14 years

Int. Cl. D9—99

U.S. Cl. D9—194

FIG. 1

FIG. 2

FIG. 3

FIG. 1 is a front view of a tooth-paste tube showing
our new design;

FIG. 2 is a rear view thereof; and
FIG. 3 is a side perspective view thereof.

We claim:

The ornamental design for a toothpaste tube, sub-
stantially as shown.
